CLAIM

The ornamental design for an ice cup with straw, as shown and described.

DESCRIPTION

FIG. 1 is a front view of an ice cup with straw showing my new design;

FIG. 2 is a side view;

FIG. 3 is an opposite side view;

FIG. 4 is a top plan view;

FIG. 5 is a bottom plan view;

FIG. 6 is a front top isometric view; and,

FIG. 7 is a front top isometric view of an ice cup with straw with the top seal opened and the straw inserted for use.

The broken lines shown of the ice cubes are for illustrative purposes only and form no part of the claimed design.
